G. W. BUSS, OF BOSTON, MASSACHUSETTS

Letters Patent No. 62,984, dated March 19, 1867.

IMPROVED CAR SPRING.

The Schedule referred to in these Letters Patent and making part of the same.

TO ALL WHOM IT MAY CONCERN:

Be it known that I, G. W. Buss, of Boston, in the county of Suffolk, and State of Massachusetts, have invented an improved Spring for Railway and other Carriages; and I do hereby declare that the following, taken in connection with the drawings which accompany and form part of this specification, is a description of my invention sufficient to enable those skilled in the art to practise it.

Letters Patent No. 36,766 were granted to me, dated October 28, 1862, on an improvement in wagons or carriages, such improvement having reference to the manner of arranging or combining a spring and lever for supporting the body of the carriage, as by reference to said patent will more fully appear. The present invention relates to the disposition of the spring and lever, (upon a series of which the carriage-body is to be supported under the same general arrangement shown in such patent,) in such manner that they are contained in a box or case, the lever and its fulcrum and the spring forming a device complete in itself and ready for application to the carriage-body in the best practical arrangement.

The invention consists, primarily, in a new article of manufacture composed of a spring, a lever and its fulcrum, and a spring-containing box, arranged and connected together, ready for application to the carriage-body. The drawings represent a device or devices embodying the invention—

A, B, C, and D showing, respectively, a side elevation, an end view, a longitudinal central section, and a cross-section through the centre of the spring.

a denotes a wrought-metal box, formed from sheet plate when hot, by bending down the sides b of the plate, and pressing them into shape by dies against the sides of a former, and finally striking down the top part c, so as to form strengthening or rigidifying beads, d, at the upper corners of the box. The central part of each side, b, of the box has a circular formation in cross-section, to receive a cylindrical rubber spring, e, and a bulging formation, as seen at f, as a provision for expansion of the sides of this spring, as it is compressed in length. At one end of the box holes are made through the side plates for bearings for a fulcrum pin, g, on which is hung a long lever, h, as seen at B, this lever extending the whole length of the box, and having an eye, i, at its free end, for attachment of the link or device through which the lever is connected with the truck or journal boxes of the car or carriage. Under the spring e the lever is spread laterally to form a head, k, to bear upon the end surface of the spring. The upper plate of the box has holes, l, formed in it, by which to secure it to the under surface of the body or frame of the car or carriage. This plate extends nearly to the end of the lever, so that the weight of the carriage resting upon the spring is borne equally over the whole surface of the frame above the lever, instead of unduly in that part of the frame immediately adjacent to the spring, as it would be were no box or plate employed, or adjacent to the end of the box, if the top plate extended only as far as the spring. This arrangement of the spring and lever is particularly applicable to horse railway carriages, being easy of application to the body of the car, and of connection with and disconnection from the truck, and affording a protection to the spring. Although I consider the swaged or struck-up formation of the box from sheet metal the most practical, yet said box may be formed of cast metal to very good advantage, and the shape of the box, the nature of the spring, and the form of the lever may be modified in various ways, retaining the essence of my invention or arrangement. One of such modifications is shown at E, which represents a cast-metal box, containing two springs and two levers, and making a convenient construction to apply transversely to the car or carriage-body. And F represents a section of a cast-metal box, containing steel elliptic springs, each of these modifications and of others which will be obvious, all-containing, however, the same relative arrangement of lever, fulcrum, spring, and box. In the employment of elliptic springs, as shown at F, the springs or plates may be graduated in thickness and strength from the lever to the innermost spring, the plates nearest the lever being the lightest. By such construction and arranging the plates as shown, the springs have a practical disposition for either light or heavy loads, without undue stress upon the light springs when a heavy load is being carried, the operation of the springs being as follows: When a light load is carried, the light springs yield readily and sufficiently, while as the load increases in weight the adjacent light springs are first compressed and brought together, and by their contact are removed from further strain, while the stronger springs receive and yield to the increase of weight.

I do not herein claim the combination of a lever, fulcrum, and spring for application to a carriage-body

and truck, such combination being shown in my patent already referred to, and my present invention relating specifically to the manner of arranging and connecting the lever, spring, and fulcrum, so as to form them into a spring device, having the bearing of the fulcrum ready for application to a carriage-body, and the free end of the lever ready for connection with the carriage truck, with provision for housing or protecting the spring and fulcrum.

I claim as a new article of manufacture a spring for railway and other carriages made up of the following combined devices, namely, an open metal box, a lever hung upon a fulcrum in one end of the box, and having its free end projecting out from the opposite end of the box for connection with the truck, and a spring interposed between the lever and the roof of the box, the box serving as a bearing for the fulcrum pin, as a means of connection between and support of the spring and lever, and as a means of applying the spring, lever, and fulcrum to the body of the carriage, the whole being arranged to operate substantially as set forth.

G. W. BUSS.
